(57) **CLAIM**

The ornamental design for a wafer carrier ring, as shown and described.

DESCRIPTION

FIG. 1 is a top perspective view of a wafer carrier ring showing our new design;

FIG. 2 is a bottom perspective view thereof;

FIG. 3 is a top plan view thereof;

FIG. 4 is a bottom plan view thereof;

FIG. 5 is a front elevational view, with the rear being a mirror image thereof;

FIG. 6 is a side elevational view, with the other side being a mirror image thereof;

FIG. 7 is a cross sectional view taken at line 7-7 of FIG. 4 and,

FIG. 8 is a cross sectional view taken at line 8-8 of FIG. 4. The broken lines shown in the figures are included for the purpose of illustrating portions of the wafer carrier ring and form no part of the claimed design.
